UNITED STATES PATENT OFFICE.

JOHN MCNEVEN, OF NEW YORK, N. Y.

INDICATOR-LOCK.

SPECIFICATION forming part of Letters Patent No. 252,120, dated January 10, 1882.
Application filed May 20, 1881. (Model.)

To all whom it may concern:

Be it known that I, JOHN MCNEVEN, of the city, county, and State of New York, have invented certain new and useful Improvements in Padlocks and in Keys for Same; and I do hereby declare the following to be a full, clear, and exact description of the same, reference being had to the accompanying drawings, forming part of this specification.

10 The object of these improvements is to produce a lock that is not liable to be picked or have the indicating mechanism tampered with or to get out of order with fair wear and tear. This padlock is virtually a double lock, having 15 two bolts and two key-holes. The lock is divided into three compartments, the lower compartment containing ratchets and check-springs that control the key-pins, as seen in Figures 7 and 9. The second compartment contains 20 the lower or principal locking-bolt and check-springs, as seen in Figs. 5, 8, and 9. The first or upper compartment contains the registering and locking bolt, as seen in Figs. 4 and 9.

In the drawings, which illustrate a padlock 25 containing my improvements, Fig. 1 is an exterior front view of the padlock. Fig. 2 is a rear view of the front plate thereof, showing the rear surfaces of the registering-wheels. Fig. 3 shows the front surfaces of such registering-wheels. Fig. 4 is a view of the upper side of the first interior plate, on which is contained the "registering-bolt," so called. Fig. 5 is a view of the upper side of the second interior plate, on which is contained the "principal locking-bolt," so called. Fig. 6 is a view of the lower side or surface of this second interior plate. Fig. 7 is a view of the inner surface of the rear plate of the padlock. Fig. 8 is a cross vertical section taken through the line $x-x$ of 40 Figs. 2, 4, and 5. Fig. 9 is a cross vertical section taken through the line $y-y$ of Figs. 2, 4, and 5. Fig. 10 is a longitudinal vertical section of the key. Figs. 11 and 12 are cross vertical sections of such key, taken through the 45 lines $z-z$ and $z'-z'$ of Fig. 10.

a is the front plate of the lock. b is the rear plate. c is the front middle plate, between which and the front plate, a , is the registering and locking bolt d . e is the rear middle plate, 50 between which and the rear plate is the principal locking-bolt f . g , g , &c., are four posts, re-

taining together the said plates. The bolt d is secured between guides or ways h , so as to have a slide motion therein according to the locking or unlocking operation. The bolt f is 55 secured and moves in a similar manner between ways i .

j , j' are key-holes. k , k' are registering-wheels, geared to each other and having numbers and letters thereon, so that each time the wheels 60 are moved in manner as hereinafter more fully explained they will present at the openings in the front plate, a , a different combination.

l , l are two arms attached to the bolt d , passing down through slots in plate c to the rear 65 of the principal locking-bolt f , so that as the locking operation is performed, the rear portion of the bolt d being acted upon by the key through the key-hole j' , both bolts will be shot forward.

m , m are check-springs to the locking-bolt f , secured to the underneath side of the rear plate, e , and which can be depressed from the upper rear surface of the plate e by the wedge-shaped sleeve n , moving in a slot in plate e , the projecting pin n' being the part against which the key will impinge to push the wedge forward in order to depress such check-springs. 75

o , o' are two key-pins, being square the distance of the first compartment only, and round 80 the rest of the distance, so that the square o' of the pipe of the key may operate to turn the click-wheel while the key is in the first compartment and to escape the square head after the key-pipe has passed into the second compartment, the pipe of the key being correspondingly formed to the key-pin—namely, the lower part of the interior of the pipe square and remainder round in cross-section. (See Figs. 10, 11, and 12.) 85

p is a lever, which is operated by the check-wheel q' , connected to the key-pin o' , so as to free its projection p' from contact with the projection p'' on the sleeve n just prior to the passage of the key to the lower compartment for 90 operation on such wedge to depress the springs m and m .

r is a spring, which comes into contact with the pins r' on the rear surface of the registering-wheel k as the bolt d is moved backward, 100 and thus moves the wheel a short distance. The click-spring s comes into contact with an-

other of said pins r' , and thus prevents the revolution of the wheel k in the reverse direction.

5 $t' t'$ are dogs and retaining-springs to the click-wheels $q' q'$.

u is a spindle, having a cap, u' , at its lower end and a spiral spring, u'' , around its body, all placed within the key, so as to enable the key with a slight pressure to adapt itself conveniently to the upper compartment of the lock, and with some additional pressure to pass down below the square head of the key-pin and into the lower compartment of the lock.

10 $v v$ are check-springs to the upper bolt, d , which, after such bolt has been shot back and the register changed, as shown in Fig. 9, prevents the bolt d being worked back and forth and working the register without first going through the whole process of unlocking. These 15 check-springs $v v$ are depressed and thrown down out of the way of the springs $m m$ of the bolt d by the passage over them of the bolt f in the unlocking operation of such latter bolt. On the locking operation the bolt f passes from 20 off these springs $v v$, and they are again active to catch and retain the springs $m m$ of the bolt d on the unlocking operation of such bolt, and consequent change of the combination of letters and figures shown by the indicating mechanism.

25 The operation of the lock is as follows: To lock, both bolts being in the position shown by the registering and locking bolt d , the key is inserted in the key-hole j' to the depth of the first compartment and turned in the direction of the arrow on Fig. 4. This carries both bolts forward into a locked position. In unlocking each bolt is separately operated. The key is first placed in the key-hole j' , depressed to the 30 second compartment, moved to the left a quarter of a circle, when the key will come up through the slot *, Fig. 4. Then, continuing the key around another quarter of a circle, the square head of the key will cause the click to operate 35 and throw off the guard-lever p from the sleeve n . Then the key is depressed back to the second compartment and turned in the direction of the arrow on Fig. 5, which will push forward the sleeve n and depress out of the way of the bolt f the check-springs $m m$. The key is then 40 placed in the key-hole j , depressed to the depth of one compartment, and turned therein in the direction of the double arrow on Fig. 4, which forces back the bolt d to the position shown in

45 Figs. 4 and 9, in doing which the spring r operates on one of the pins r' of wheel k (one of the geared-together indicating-wheels,) and thereby changing the combination of figures and letters thereon, and also by means of the arms $l l$, passing to the rear of the check-springs $v v$, prevents the bolt d being moved forward and backward until the whole unlocking and locking operation is gone through with again. The key is continued around to the extent of a semicircle, when it will pass down into 50 the next compartment, and then by a movement in the reverse direction, as shown by the double arrow on Fig. 5, the principal locking-bolt f is shot back, and this carries out of the way of the arms $l l$ the springs $v v$, in manner 55 as hereinbefore explained, so that both bolts will coincide and be free for forward movement together in the locking operation. The bolt f in the locking operation permits the check-springs $m m$ at its rear to rise, as in unlocking the bolt f has pushed back the wedge n from out of such contact with such springs and from holding them in a depressed position, which position they were placed in by the 60 first operation in unlocking of moving forward 65 the wedge n , and thus depressing the springs $m m$ by entering in between their base-plate m' and the plate e , to which such base-plate is riveted.

70 I claim—

1. In an indicator-lock, the combination of a locking-bolt, d , a second principal locking-bolt, f , check-springs for each of said bolts, and the wedge-shaped sleeve n , to depress the check-springs $m m$, substantially as described.

75 2. In an indicator-lock, the combination of the locking and unlocking wedge n with the check-springs $m m$ and the lever p , substantially as described.

80 3. In an indicator-lock, the combination of the registering-wheels $k k'$, the bolt d , and the principal locking-bolt f , substantially as described.

85 4. In an indicator-lock, the combination of the registering-wheels $k k'$, the bolt d , the principal locking-bolt f , and the respective check-springs to said bolts, substantially as described.

JOHN MCNEVEN.
